United States Patent

Des. 241,795
Patented Oct. 12, 1976

241,795

CHAIR

Lee Harold Fister, Jr., 7715 Park Creek Drive,
Dayton, Ohio 45459

Filed Feb. 10, 1975, Ser. No. 548,275

Term of patent 14 years

Int. Cl. D6—01

U.S. Cl. D6—71

FIG. 2

FIG. 1

FIG. 3

FIG. 4

FIG. 5

FIG. 6

FIG. 1 is a perspective view illustrating one side and the top of a chair constructed in accordance with the invention;

FIG. 2 is a side elevational view of the opposite side;

FIG. 3 is a front elevational view thereof;

FIG. 4 is a view similar to FIG. 3 except illustrating the condition when the chair is used;

FIG. 5 is a rear elevational view thereof;

FIG. 6 is a bottom plan view thereof.

I claim:

The ornamental design for a chair, as shown and described.
